UNITED STATES PATENT OFFICE

CHARLES O. BALL, OF BIRMINGHAM, MICHIGAN, ASSIGNOR TO YELLOW TRUCK AND COACH MANUFACTURING COMPANY, OF PONTIAC, MICHIGAN, A CORPORATION OF MAINE

INTERLOCK MECHANISM

Application filed October 21, 1927. Serial No. 227,747.

This invention relates to motor vehicles of the so-called gas-electric type, wherein an internal combustion engine is utilized to drive an electric generator, which in turn develops electrical energy to operate one or more motors connected with the driving wheels. More particularly, the invention pertains to an inter-lock between the control lever governing transmission of electric current to the motor and the starter switch for the explosive engine, for the purpose of eliminating possibility of accidental starting when the controller lever is in other than neutral position.

With power units of this type, it is highly desirable that the controller be in neutral position when the engine is first started. In practice, it has been found that the operator occasionally will step on the engine starter button and accelerator pedal simultaneously with the result that when the engine starts, current in considerable quantity is provided by the generator, and if the controller is in any position but neutral, the vehicle will move either ahead or back depending on controller position. It is quite obvious that these conditions present a grave accident risk, and it is to avoid these conditions with which the present invention is primarily concerned.

A further object of the invention is to provide a simple and inexpensive assembly of parts which will be economical in manufacture, easy to install and operate, positive and foolproof in action, and unlikely to get out of repair or require attention in use.

Other incidental objects and features of advantage will be apparent from the following detailed specification and the accompanying drawings, in which drawings Figure 1 is a diagrammatic top plan view of an automobile chassis showing in a general way, a typical arrangement of the various units employed on gas-electric vehicles, the wiring connections between the parts, and the application of the present invention thereto; Figure 2 is a side elevation of the controller lever and interlocking mechanism, with the controller lever moved out of neutral position; Figure 3 is a similar view on a slightly larger scale with the lever in neutral or "off" posi-

tion; Figure 4 is an end view partly in section and Figure 5 is a top plan view, of the structure shown in preceding figures.

Referring first to the diagrammatic illustration, Figure 1, the reference character 1 indicates the chassis frame assembly mounted on road wheels in the usual manner, which carries an internal combustion engine 2 in the fore part thereof. To initiate operation of the combustion engine a starting system is provided, preferably consisting of an electric motor or starter 3, which turns the engine over by engagement with the engine flywheel, when the switch 4 is closed to supply current to the motor from a storage battery 5. Subsequent operation of the gas engine, depending upon the amount of fuel fed thereto, drives an electric generator or dynamo 6, which transforms mechanical energy of the gas engine into electric current. This, in turn, drives an electric motor 7, connected with the rear wheels to propel the vehicle. Transmission of the electric current from the generator to the motor is under control of the operator or driver, by the manipulation of a hand operated shift lever 8, connected with a controller or circuit changer 9, whereby the movement of the lever from neutral position, permits various circuit connections to be established for propelling the vehicle either forward or backward and at different speeds, in accordance with the position to which the control lever is moved.

It may be observed that the controller 9, in no sense affects generation of current but simply acts as a switch, placing the wiring of the motor in several different combinations, in or out of the generator circuit. It is obvious that however much the operator may race his engine with the controller in neutral position, the vehicle will not move unless by gravity or some other external force. In order therefore, to eliminate possibility of transmission of electric energy to the driving motor upon initial starting of the engine, it is here proposed to permit closing of the starter switch only upon condition that the controller lever is in such neutral position.

To this end there is shown in Figures 2 to 5 inclusive, a preferred arrangement of parts,

wherein the controller lever 8 and starter switch 4 extend through the floor of the vehicle adjacent each other. A bracket or plate 10 fixedly secured on the lower end of the lever 8, is pivotally mounted on a shaft 11 carried by the member 12, inclosing the lower end of the lever. Integral lugs or ears 13 on the member 12, are secured by bolts 14 to the floor of the vehicle, the bolts at one side also serving to fasten the plate 15, to which is hingedly or pivotally mounted on an axis substantially at right angles to that of the shaft 11, a bracket or lever 16. This bracket or lever 16 has a cup-shaped portion or foot 17 overlying and surrounding the top of a button or stem 18 of the starter switch, which upon depression closes the circuit leading to the starting motor 3. Depression of the starter button 18, therefore, is controlled by the downward pivotal movement of the lever 16. As shown in Figure 4, the contacting surfaces are preferably in the form of rounded knobs on the bottom of the cup-shaped foot 17 and top of the button 18, to permit the parts to slide more freely on each other. The opposite end of the pivoted lever or bracket 16 extends upwardly beside the controller lever in the form of a fan shaped or quadrant portion 19, which is preferably a segment of a circle having a center of curvature substantially at the pivotal axis at the lever 8, so as to conform with the arc described by a lateral projection carried on the lever 8. The peripheral edge of the quadrant or sector portion 19 is cut away or notched as at 20, at a point which coincides with the position of said lateral projections when the control lever 8 is in a neutral position of control. This lateral projection comprises a U-shaped member 21 extending on either side of the lever 8, and a stud 22 passing through aligned apertures in the member 21 and lever, and carrying a sleeve 23 screw threaded thereon, with a lock washer 24 interposed between the member 21 and sleeve 23.

It will be apparent that when the lever 8 is in neutral position, the notch 20 clears the sleeve 23, permitting movement of the lever 16 by depression of the portion 17 to operate the starter switch 4. At such time the sleeve 23 extends within the notch. If desired the sleeve 23 may be provided adjacent its end with an annular enlargement or peripheral ring 25 to serve as a stop against outward tilting of the sector 19, and so limit the extent of pivotal movement of the lever 16 in one direction. To limit the movement of the lever 16 in the opposite direction, an adjustable set screw 26, provided with a lock nut 27, may be carried by the lever for engagement with the wall of the stationary supporting member 12. On the other hand when the lever is moved out of neutral position the projection overlies the peripheral edge of the segment and the engagement of these parts

holds the lever 16 against swinging movement. Thus the control elements are arranged in interlocking relation, and so long as the controller is in a position that permits transmission of energy from the generator to the motor, it will be impossible to start the engine. Since, therefore, the generation of current may be initiated only when the generator circuits are open, no power will be supplied the propelling motor and a stationary position of the vehicle is insured.

While the invention has been described in terms that are more or less specific, it is to be understood the invention is not limited to exact details shown, but that it is capable of such modifications as come within the scope of the appended claims.

Having described my invention, I claim:

1. Interlock mechanism of the character described, including in combination with a pair of pivoted control elements having axes arranged in angular relation, of a lateral projection on one of the elements extending in proximity to a portion of the other element, said portion having a curved surface conforming to and lying in the arc of movement of the projection and having an opening therein corresponding to the location of said projection when the first mentioned element is in a predetermined position of control, the curved surface of said portion being adapted to abut the projection to lock the second mentioned element against movement when the first mentioned element is out of said predetermined control position and said projection extending within said opening during movement of the second mentioned element to hold the first mentioned element against movement out of said predetermined control position.

2. Interlock mechanism of the character described, including in combination with a pair of pivoted control elements having pivotal axes arranged in angular relation, of a lateral projection on one of the elements, an extension on the other element of sector-shape substantially conforming to the arc inscribed by said projection, the peripheral edge of which is adapted to engage said projection to hold the last mentioned element stationary when the first mentioned element is positioned within a predetermined range of its movement, the continuity of said peripheral edge extending throughout the corresponding path of movement of said projection while the first mentioned element is within said predetermined range of movement but ending therebeyond to permit the movement of the second mentioned element when the first mentioned element is outside said range.

3. The combination set forth in claim 2, wherein said lateral projection is provided with an enlarged peripheral ring adjacent the end thereof which is adapted for engage-

ment with the side of the sector shaped extension to limit swinging movement of the control element.

4. The combination set forth in claim 2 wherein a stop member is carried on said projection and is adapted for engagement with said extension to limit the swinging movement of the control element in one direction.

5. The combination set forth in claim 2, wherein a stop member is carried on said projection and is adapted for engagement with said extension to limit the swinging movement of the control element in one direction, and a second stop member is adjustably mounted on the control element for abutment with a stationary part to limit its movement in the opposite direction.

6. An interlock of the character described, including in combination with a switch, and a control lever pivotally mounted adjacent thereto, of a pivoted member having its pivotal axis substantially at right angles to that of said lever, and having a portion thereof overlying and by its movement controlling the closing of said switch, and having another portion formed as a quadrant of a circle whose center is approximately the pivotal axis of said lever, a projection on the lever for engagement on the peripheral surface of the quadrant to hold said pivoted member against movement, the peripheral surface being cut away at a point coinciding with the location of said projection when the lever is in a predetermined position of control, to permit movement of said member to close the switch only when said lever is in such predetermined position of control.

7. Interlock mechanism associated with a pair of control elements of a motor vehicle or the like to prevent manipulation of either element when the other is in a predetermined position of adjustment, including a pair of pivoted levers having their axes of oscillation arranged transversely of each other, a quadrant shaped portion on one of the levers, whose curved surface, when the lever is in an inoperative position, forms an arc of a circle, with a center substantially on the axis of pivotal movement of the other lever, and a stop carried by the last mentioned lever adapted for abutment with said curved surface.

In testimony whereof I affix my signature.
CHARLES O. BALL.
